UNIFORM IMPEDANCE NETWORK

Harold A. Wheeler, Great Neck, N. Y., assignor to
Hazeltine Corporation, a corporation of Delaware

Application August 26, 1937, Serial No. 161,017

12 Claims.

(Cl. 178—44)

This invention relates generally to uniform impedance networks and is particularly useful in matching the image impedance of an exponential line with the impedance of a circuit or with the image impedance of another line to which the exponential line is to be connected, particularly a uniform line having a purely resistive and uniform image impedance. The invention is particularly suitable for utilizing an exponential 5 transmission line as means for coupling an antenna to a uniform line going to the terminal circuit of a modulated-carrier signal apparatus.

In order that two transmission circuits may be coupled together in such manner that there are 10 no reflections from the junction, it is necessary that the circuits have, at their junction, image impedances which are properly matched over the entire range of frequencies to be transmitted. Exact matching over a wide range of frequencies 15 is impossible if the image impedances of the circuits to be connected have dissimilar variation with frequency. For example, it is impossible if only one of the image impedances has a complex value. If the image impedances are both purely 20 resistive over the range of frequencies for which image impedance matching is required, the circuits can be matched by the use of filter sections, including a transformer if it is necessary to change the impedance level at the junction. 25 However, a transformer can be included only in a band-pass filter of limited frequency range and for this reason may be unsatisfactory where it is required to pass a wide range of frequencies.

It has previously been proposed to use a transmission line having distributed impedance which varies exponentially with the length of the line for coupling two circuits which have different impedance levels. One such arrangement is disclosed in United States Patent No. 1,927,522, granted September 19, 1933, on an application of Nils E. Lindenblad. It is there proposed to utilize a simple impedance-matching filter or line device to match the image impedance of an exponential line with the impedance of one of the 30 circuits to be coupled. However, it is now recognized that an exponential line of generalized 35 length has an image impedance which is not a pure resistance and which cannot, therefore, be matched with the impedance of a load circuit by 40 a simple filter.

Various attempts have been made to obtain 45 approximate matching between such a line and the circuit to which it is coupled. In United States Patent No. 2,018,320, granted October 22, 50 1935, on an application of Walter van B. Roberts,

it is suggested that the image impedance may be kept nearly pure resistance if the rate of taper is made sufficiently small and the line is made sufficiently long to secure the desired impedance ratio.

An approximate matching of impedance between an antenna and a radio receiver by means of a tapered line is disclosed in "Radio Service Notes" of General Electric Company (1935), at pages 13, 14, and 15, in an article entitled "'V-Doublet' Antenna System." However, this line comprises tapered straight conductors and, thus, is only a poor approximation of the coupling which would be provided by an exponentially tapered line.

It has also been proposed to use an exponential line connecting an antenna with the input circuit of a modulated-carrier signal receiver, but in each of the previous proposals the line is not ideally matched at its junctions with the adjacent circuits. Such a proposal is found in the Roberts patent mentioned above. As another example, it has been proposed to provide an antenna coupling circuit wherein a single wire having an exponentially tapered impedance to 25 ground is used, in which case the capacitance and inductance exist with respect to ground. Such a disclosure is found in Australian Patent No. 18,994, accepted August 30, 1929. However, in these cases, the exponential line does not have 30 at its junctions even approximate matching of image impedance over a considerable range of frequency.

It is an object of the present invention, therefore, to provide a uniform impedance network 35 having a substantially uniform responsiveness over a wide range of frequencies.

It is another object of the present invention, therefore, to provide a terminating circuit for an exponential transmission line of any taper and length, by means of which the matching of image impedances is independent of frequency.

It is a further object of the invention to provide an antenna-coupling circuit, the transmission band of which covers a wide range of frequencies.

In accordance with the invention, means are provided for terminating an exponential line of any taper and length, by means of which the image impedance of the line can be exactly 50 matched by a filter having either a mid-shunt or a mid-series termination. In a transmission line having such a termination, ordinary filter theory with reference to confluent constant- k and m -derived filters is applicable.

More particularly, the image impedance of an exponential line is exactly matched with the image impedance of a constant- k filter having either a mid-shunt or a mid-series termination by power factor correction which converts the image impedance of the line into a pure resistance which varies with frequency. An m -derived filter section can be added to match closely the variable resistive image impedance to a constant resistance. Thus, by the use of the invention, any circuit having a resistive image impedance over the range of frequencies to be transmitted can be exactly matched with an exponential line of any length and of such taper as to pass the given range of frequencies. Since the impedance level is modified in the exponential line without the undesirable filter characteristics resulting from the use of a transformer for changing the impedance level, an exponential line having terminal circuits in accordance with the invention provides an improved means for connecting two circuits having impedances of different levels and provides an ideal means of connecting two circuits having resistive image impedance terminations of different levels; and provides an ideal means of connecting two circuits having resistive image impedance terminations of different impedance levels. Further, in accordance with the invention, means are provided whereby an exponential transmission line terminates in an image impedance almost exactly matching that of a doublet antenna for all frequencies of the transmission band.

For a better understanding of the present invention, together with other and further objects thereof, reference is had to the following description, taken in connection with the accompanying drawings, and its scope will be pointed out in the appended claims.

Fig. 1 of the drawings is a schematic representation used for deriving the equations of an exponential line; Fig. 2 is a schematic diagram of the image impedance of an exponential line resolved into series components; Fig. 3 is a schematic diagram of the image impedances of an exponential line resolved into parallel components; Fig. 4 is a graph of the image impedances of an exponential transmission line both below and above the cutoff frequency; Fig. 5 illustrates a circuit arrangement for matching the line image impedance with the corresponding constant- k filters by resolving into series components; Fig. 6 illustrates a circuit arrangement for obtaining an approximately constant image resistance; Fig. 7 shows a balanced disposition of the elements of Fig. 6; Fig. 8 is a graph of the relation between wire separation and distance from the point of maximum separation for lines having various given ratios of maximum separation to wire diameter; Fig. 9 illustrates as a special case one of the transmission lines, the characteristics of which are shown in Fig. 8; Fig. 10 shows a circuit arrangement for substantially matching the impedance of an exponential line with a doublet antenna; and Fig. 11 shows a circuit arrangement for matching a vertical-wire antenna with a single-wire exponential line having a ground return circuit.

In setting forth the invention, it is necessary to use a mathematical analysis. The properties of the ideal exponential line may be derived with reference to Fig. 1. It is assumed that there

is no dissipation and that the line is tapered in accordance with the formulae:

$$L_1/L_{1a} = C_{1a}/C_1 = e^{4\pi z/\lambda_c} = 10^{5.46 z/\lambda_c} \quad (1)$$

in which L_1 and C_1 are the inductance and capacitance per unit of length, z is the distance along the wires from the narrow end (the end denoted by subscript a), and λ_c is the "cutoff wavelength" to be identified below. It is also assumed that the separation is much less than the wave length in space at all frequencies of interest.

The usual line equations are:

$$dE/dz = -Ij\omega L_1; dI/dz = -Ej\omega C_1 \quad (2)$$

in which E and I are vectors of alternating voltage and current along the line. There is assumed, subject to justification below, a progressive wave, free of terminal reflections, starting at the narrow end (subscript a):

$$E = E_a e^{2\pi(z/\lambda_c - jz/\lambda)}; I = I_a e^{2\pi(-z/\lambda_c - jz/\lambda)} \quad (3)$$

in which λ is the wave length along the line at the operating frequency. Also,

$$dE/dz = 2\pi(1/\lambda_c - j/\lambda) E_a; dI/dz = 2\pi(-1/\lambda_c - j/\lambda) I_a$$

Substituting in Equations 2, the exponential terms cancel out, thereby justifying the assumed progressive wave of Equations 3. There remain the relations,

$$2\pi(1/\lambda_c - j/\lambda) E_a = -I_a j\omega L_{1a} \quad (4)$$

$$2\pi(-1/\lambda_c - j/\lambda) I_a = -E_a j\omega C_{1a} \quad (5)$$

Solving for the wave length:

$$4\pi^2(1/\lambda_c^2 + 1/\lambda^2) = \omega^2 C_{1a} L_{1a} \quad (6)$$

Let $2\pi/\lambda_c = \omega_c/v_0$; $2\pi/\lambda = \omega/v$

in which ω_c is the cutoff frequency of the line and v is the steady-state wave velocity along the wires, having a limiting value of v_0 at high frequencies. Therefore, from (5) and (6), the limiting velocity (at infinite frequency) is

$$v_0 = 1/\sqrt{C_{1a} L_{1a}} \quad (7)$$

and the actual velocity is

$$v = v_0/\sqrt{1 - \omega_c^2/\omega^2} \quad (8)$$

If the wires have negligible dissipation and are located in air, v_0 is nearly the velocity of light. The steady-state wave velocity along the wires is greater, becoming infinite at the cutoff frequency ω_c . The cutoff wave length λ_c is, in this case, approximately the wave length in air at the cutoff frequency. This is a convenient parameter for design, whereas the actual wave length in the line is infinite at the cutoff frequency. At lower frequencies, the velocity is imaginary, which denotes attenuation as distinguished from wave transmission.

In the case mentioned, the steady-state velocity is variable and is greater than the limiting velocity which is nearly the velocity of light. It is a form of distortion which is absent in the ideal uniform line, but is found in filters. The "group velocity" or "impulse velocity" does not really exceed that of light, although the "phase velocity" or "steady-state velocity" are greater, as effected by the taper.

The image impedance of the line at the narrow end is the driving-point impedance of the

progressive wave assumed in (3); it is obtained by solving (4) and substituting from (6):

$$Z_a = E_a/I_a = (v_0/v - j\omega_c/\omega) \sqrt{L_{1a}/C_{1a}} \quad (9)$$

In further expressions, it is convenient to use the image resistance R_k of any small section of the line, so short that its taper can be neglected:

$$R_k = \sqrt{L_1/C_1} = R_{ka} e^{4\pi l/\lambda_c} \quad (10)$$

The line is comparable with a transformer whose turns ratio is

$$T = \sqrt{R_{kb}/R_{ka}} = e^{2\pi l/\lambda_c} = 10^{2.73 l/\lambda_c} \quad (11)$$

in which l is the length of the line. It appears that a nominal ratio can be secured with a length only a small fraction of λ_c .

In the transmission band, above the cutoff frequency ω_c , the exponential line has a complex image impedance of constant magnitude. The real (resistive) component of the latter is equal to the image impedance (resistance) of a constant- k high-pass filter having the same cutoff frequency. The imaginary (reactive) component of the complex image impedance is such that the exponential line can still be matched exactly with a constant- k high-pass filter. The imaginary component always can be represented by an actual inductance or capacitance. The real component varies with frequency and, therefore, cannot be represented by an actual resistance.

The image impedance of the exponential line, looking respectively into the low-impedance (narrow) and high-impedance (wide) ends, is given by the following expressions, in which the subscripts a and b denote the respective ends:

$$R_{ka} = \sqrt{L_{1a}/C_{1a}}; R_{kb} = \sqrt{L_{1b}/C_{1b}} = R_{ka} e^{4\pi l/\lambda_c} \quad (12)$$

$$Z_a/R_{ka} = \sqrt{1 - \omega_c^2/\omega^2} - j\omega_c/\omega = \frac{1}{\sqrt{1 - \omega_c^2/\omega^2} + j\omega_c/\omega} \quad (13)$$

$$Z_b/R_{kb} = \sqrt{1 - \omega_c^2/\omega^2} + j\omega_c/\omega = \frac{1}{\sqrt{1 - \omega_c^2/\omega^2} - j\omega_c/\omega} \quad (14)$$

The latter is obtained in the same manner as the former, the opposite sign of ω_c denoting the effective opposite taper toward the backward wave.

The square root term in each of Equations 13 and 14 is equal to the relative mid-series image impedance or mid-shunt image admittance of the corresponding constant- k high-pass filter having the same cutoff frequency. In the transmission band above the cutoff frequency, the square root term is real and positive. In the attenuation band below the cutoff frequency, the square root term is imaginary and negative. The remaining term in the above expressions is imaginary and its sign depends on which end of the line is represented.

Fig. 2 shows the resolution of Z_a and Z_b into series components, as follows:

$$Z_a = R_a + jX_a = R_a + 1/j\omega(2C_a) \quad (15)$$

$$R_a = R_{ka} \sqrt{1 - \omega_c^2/\omega^2}; X_a = -1/\omega(2C_a); 2C_a = 1/\omega_c R_{ka} \quad (16)$$

$$Z_b = R_b + jX_b = R_b + 1/j\omega(-2C_b) \quad (17)$$

$$R_b = R_{kb} \sqrt{1 - \omega_c^2/\omega^2}; X_b = 1/\omega(2C_b); 2C_b = 1/\omega_c R_{kb} \quad (18)$$

These relations are valid only in the transmission band, where R_a and R_b are equal to the mid-

series image resistance of the corresponding filters.

Fig. 3 shows the resolution of Z_a and Z_b into parallel components, as follows:

$$1/Z_a = 1/R_a' + 1/jX_a' = 1/R_a' + 1/j\omega(-2L_a) \quad (19)$$

$$R_a' = R_{ka}/\sqrt{1 - \omega_c^2/\omega^2}; X_a' = \omega(-2L_a); 2L_a = R_{ka}/\omega_c \quad (20)$$

$$1/Z_b = 1/R_b' + 1/jX_b' = 1/R_b' + 1/j\omega(2L_b) \quad (21)$$

$$R_b' = R_{kb}/\sqrt{1 - \omega_c^2/\omega^2}; X_b' = \omega(2L_b); 2L_b = R_{kb}/\omega_c \quad (22)$$

These relations are valid only in the transmission band, where R_a' and R_b' are equal to the mid-shunt image resistance of the corresponding filter.

In Figs. 2 and 3, the quantities C_a , L_a and C_b , L_b are the full-series and full-shunt elements of the corresponding filter. These quantities doubled are the respective mid-series and mid-shunt elements. This relation forms the basis for matching the corresponding line and filter terminations.

Fig. 4 shows graphically the image impedance and its components at either end of the exponential line. The abscissae are inversely proportional to frequency, to show concisely the limiting conditions at high frequency. The abscissae between 0 and 1 thus represent the transmission band of the exponential line. It will be seen that in this band the image impedance of either end of the line is a constant, the image impedances being represented by Z_a and Z_b , respectively. In the transmission band the image impedance Z_a can be resolved into series components R_a' and $-X_a$, or parallel components R_a ' and $-X_a$ ', as illustrated. Similarly, the impedance Z_a in the transmission band can be resolved into either series or parallel components, as shown. In the attenuation band, that is, beyond point 1 on the abscissae, the image impedance of the line at either end is a pure reactance and is shown represented by Z_a or X_a and Z_b or X_b for the respective ends of the line.

Matching the exponential line with adjacent circuits involves not only the relative magnitudes of the impedances at the junction, but also the nature of the line impedance. The line impedance approximately matches a constant resistance (R_{ka} or R_{kb}) only at frequencies much higher than the cutoff frequency. Closer matching is secured by "power-factor correction" which converts the line impedance to a pure resistance variable with frequency and by means of which either end of the line can be matched exactly with a high-pass constant- k filter. An m -derived termination of such a filter can be used to match closely a constant resistance.

Fig. 5 shows the principle of power-factor correction of the line impedance. The image impedance at the narrow end of the line is represented, as in Fig. 2, by R_a in series with $2C_a$ (in dotted lines). The effect of reactance of $2C_a$ is cancelled by connecting $2L_a$ in parallel, while the resistance R_a is transformed to R_a' , which is the mid-shunt image resistance of the corresponding constant- k filter, by means of the half-section high-pass filter 3 formed by $2C_a$ and $2L_a$. The wide end is also represented, as in Fig. 2, by R_b in series with $-2C_b$. The effect of the reactance $-2C_b$ is cancelled by connecting $2C_b$ in series, leaving purely resistive image impedance R_b' , which is the mid-series image resistance of the corresponding constant- k filter.

It is noted that the elements added for power-factor correction, $2L_a$ and $2C_b$, comprise together a half-section filter, divided by the line.

Fig. 5 shows also the matching of the line with 5 half-sections of a constant- k high-pass filter. At the narrow end, R_a' is the mid-shunt image impedance of the half-section 4, the mid-series image impedance of which is R_a . At the wide end, R_b is the mid-series image impedance of the half-section 5, the mid-shunt image impedance of which is R_b' . Any number of half-sections may be added, according to the ordinary rules of filter design.

The two essential requirements of impedance 15 matching are met by the line and filters of Fig. 5. First, each terminal circuit presents to the line an image impedance equal to that of a continuation of the line with the same exponential taper. For example, at the wide end, $2C_b$ and R_b in 20 series result in the same image impedance at the narrow end as a continuation of the line at the wide end without interruption. Secondly, each end of the line with its power-factor correction presents to the respective filter an image 25 impedance equal to that of the adjoining filter termination.

Since the "constant- k " image resistances R_a , R_a' , R_b , and R_b' vary with frequency, they are not very nearly matched with a constant-resistance circuit. The matching is greatly improved by the use of an m -type half-section between the constant-resistance circuit and the constant- k image resistance of the line or filter section. In Fig. 5, for example, the half-section 30 at either end may be replaced by an m -type half-section. The complete circuit at either end then becomes that of Fig. 6. The circuits of Fig. 7 are equivalent to those of Fig. 6, but are arranged to have bilateral symmetry so that the 35 system may be balanced relative to ground. Figs. 6 and 7 provide nearly exact matching, at frequencies above the cutoff frequency, between the ends of the exponential line and the constant resistances R_{ka} and R_{kb} . The choice of the filter 40 design parameter m determines the residual relative variations of the image resistances at the terminations in Figs. 6 and 7. A value of m equal to 0.6 is suggested, which causes the image resistances to be within about 5 percent of the 45 respective terminating resistances R_{ka} or R_{kb} at all frequencies more than 15 percent above the cutoff frequency. This value of m also places the "frequency of infinite attenuation" 20 percent below the cutoff frequency.

The circuits of Figs. 6 and 7 are about the 55 simplest that can be used to match closely either end of an exponential line with a constant-resistance circuit, such as a uniform line. If an exponential line without the matching expedients 60 of Fig. 5 or Fig. 6 is connected directly to a constant-resistance circuit, the matching will not be satisfactory at frequencies less than 40% above the cutoff frequency because the power factor of the line impedance is then substantially less than 65 70 percent. If the circuit arrangement of Fig. 5 is used to match an exponential line with a constant-resistance circuit, so that the effective image impedance of the exponential line is purely resistive but variable with frequency, the constant-resistance circuit should have a resistance value which is the geometric mean of the minimum and maximum values of the nonuniform effective image resistance of the exponential line, over the required frequency range. For example, if the system is to pass all frequencies more

than 40% above the cutoff frequency, the constant resistance should be about 0.84 R_a to match R_a or about 1.19 R_b to match R_b .

A two-wire transmission line has an exponential taper only when the separation of the wires varies correctly with distance along the wires. If the desired variation of R_k is given, in accordance with Equation 2, the actual values of R_k determine the ratio of separation to wire diameter at all distances. An explicit formula for the separation in terms of the distance, may be derived on the assumption of bare wires of zero resistance.

Referring to Fig. 1 and Equation 2,

$$\frac{R_k}{R_{ka}} = \frac{\log_e \frac{4y}{d}}{\log_e \frac{4y_a}{d}} = e^{4\pi z/\lambda_c} \quad (23)$$

in which d is the wire diameter, y is half the separation, and z is the distance measured along the wire. This equation yields the solution,

$$\frac{4y}{d} = \left(\frac{4y_a}{d} \right) e^{4\pi z/\lambda_c} \quad (24) \quad 25$$

There is a maximum separation, beyond which this formula cannot be satisfied, because the separation would have to increase more rapidly than the distance along the wire. The maximum separation is defined by the relation:

$$\frac{dy}{dz} = 1 \quad (25)$$

From Equation 24

$$\frac{dy}{dz} = \frac{\pi d}{\lambda_c} \log_e \frac{4y_a}{d} \cdot e^{4\pi z/\lambda_c} \left(\frac{4y_a}{d} \right) e^{4\pi z/\lambda_c} \quad (26)$$

Since z is measured from an arbitrary datum point, Equations 24 and 26 can be rewritten as:

$$\frac{4y}{d} = \left(\frac{4y_a}{d} \right) e^{4\pi z'/\lambda_c} \quad (27)$$

and

$$\frac{dy}{dz'} = \frac{\pi d}{\lambda_c} \log_e \frac{4y_a}{d} \cdot e^{4\pi z'/\lambda_c} \left(\frac{4y_a}{d} \right) e^{4\pi z'/\lambda_c} \quad (28) \quad 45$$

where $z' = 0$ at the point of maximum separation. This greatly simplifies Equation 26 and enables its solution simultaneously with Equation 24. This solution involves the wire diameter d , the cutoff wave length λ_c , and the maximum half-separation y_m . It is expressible in any of several forms, but an explicit solution for y_m is impossible.

$$\lambda_c = 4\pi y_m \log_e \frac{4y_m}{d} \quad (29)$$

$$\frac{\lambda_c}{\pi d} = \frac{4y_m}{d} \log_e \frac{4y_m}{d} \quad (30) \quad 60$$

$$\frac{\lambda_c}{y_m} = 4\pi \log_e \frac{4y_m}{d} \quad (31)$$

$$\frac{4y_m}{d} = e^{\lambda_c/4\pi y_m} \quad (32) \quad 65$$

$$d = \frac{4y_m}{e^{\lambda_c/4\pi y_m}} \quad (33)$$

The separation of the wires along the length of the exponential line is best expressed in terms of the ratio y/y_m , which is always less than unity. In order to make this expression as simple as possible, z' is measured from the point of maximum separation. At all points of less separation and, therefore, at all other possible points,

z' is negative. The following formula gives an explicit solution for y .

$$\frac{y}{y_m} = \left(\frac{d}{4y_m} \right)^{1-e^{-p}} \quad (34)$$

in which

$$p = \frac{-z'}{\log \frac{4y_m}{d}} \quad (35)$$

The following formula gives an explicit solution for z' .

$$\frac{-z'}{y_m} = \log \frac{4y_m}{d} \log \frac{\log \frac{4y_m}{d}}{\log \frac{4y}{d}} \quad (36)$$

The shape of an exponential line near the point of maximum separation ($z'=0$), as computed by Formula 34, is nearly independent of the wire diameter d , in practical cases where the latter is very small as compared with the maximum half-separation y_m . A convenient criterion for the shape is the ratio y_m/d . Fig. 9 shows the shape of an exponential line having a ratio $y_m/d=1000$, which is a practical value.

Fig. 8 is plotted from Equation 36 in such a manner as to show the variation of separation with distance along the wires from the point of maximum separation. The ratio y_m/d is used as a parameter. Interpolation is possible for values of this ratio between 100 and 10,000. These curves are most useful in the design of exponential lines.

Fig. 10 illustrates the matching of a uniform transmission line 10 with a straight-wire doublet 11, 12. The following procedure is useful in designing an exponential line 13 for this use according to the above principles and relations.

The cutoff wave length $\lambda_c=100$ meters, the wire diameter $d=0.2$ centimeter, and the uniform line separation $D=10$ centimeters are assumed.

The ratio $\lambda_c/100d$ is 500. By plotting Equation 30, y_m/d is found to be 520; from Equation 31, λ_c/y_m is found to be .96; therefore, the half maximum separation y_m is equal to 104 centimeters.

The minimum half-separation is $D/2=5$ centimeters=.048 y_m . Reading opposite $y/y_m=.048$ in Fig. 8, it is found that the exponential taper will require a length of wire equal to 3.9 y_m , about 4 meters. Also, the variation of separation along the wires is determined from the curves of Fig. 8. The shape is substantially like that shown in Fig. 9.

Tension cords or separators 14 are connected between the tapered wires, at intervals sufficiently close to maintain substantially the correct shape. The straight wire of the doublet is cut out in the center at 15 for a space of about 2 meters, and the wide end of the tapered line 13 is connected in this space. No matching filter is required at the doublet end of the tapered line of Fig. 10, because the rate of taper decreases gradually in the doublet itself. The above design procedure may be easily modified to fit any given set of conditions. The narrow end of the exponential line is matched to the uniform line by a terminating circuit 16 using the principles illustrated in Fig. 6 or 7.

Fig. 11 illustrates the principle of matching a uniform transmission line 17 having a ground return with a vertical antenna 18. The same design principles illustrated with reference to Fig. 10 are used to design a single wire 19 having a

ground return and having its constants exponentially varying along its length.

While there have been described what are at present considered the preferred embodiments of this invention, it will be obvious to those skilled in the art that various changes and modifications may be made therein without departing from this invention, and, therefore, it is aimed in the appended claims to cover all such changes and modifications as fall within the true spirit and scope of this invention.

What is claimed is:

1. A wave-signal translating system comprising a transmission line having an impedance which varies exponentially along the length of the line and a terminating circuit for one end of said line comprising auxiliary reactance means proportioned to adjust the image impedance at said end to an impedance exactly equal, over all frequencies of the transmission band of said line, to the image impedance of a constant- k high-pass filter section having the same cutoff frequency.

2. A wave-signal translating system comprising a transmission line having an impedance which varies exponentially along the length of the line and a terminating circuit for said line comprising an inductance having a value of

$$\frac{1}{\omega_c} \sqrt{\frac{L_{1a}}{C_{1a}}} \quad 30$$

in parallel with said line at the end of the line having the lower impedance level, where ω_c is the cutoff frequency of said line and L_{1a} and C_{1a} are, respectively, the inductance and capacitance per unit length of said line at said end, said first-mentioned inductance thereby adjusting the image impedance of said line at said end to a pure resistance over the transmission band.

3. A wave-signal translating system comprising a transmission line having an impedance which varies exponentially along the length of the line and a terminating circuit for said line comprising a capacitance having a value of

$$\frac{1}{\omega_c} \sqrt{\frac{C_{1b}}{L_{1b}}} \quad 45$$

in series with said line at the end of the line having the higher impedance level, where ω_c is the cutoff frequency of said line and L_{1b} and C_{1b} are, respectively, the inductance and capacitance per unit length of said line at said end, said first-mentioned capacitance thereby adjusting the image impedance of said line at said end to a pure resistance over the transmission band.

4. A wave-signal translating system comprising a transmission line having an image impedance which varies exponentially along the length of the line and a terminating circuit for said line comprising an inductance having a value of

$$\frac{1}{\omega_c} \sqrt{\frac{L_{1a}}{C_{1a}}} \quad 65$$

in parallel with said line at the end of the line having the lower impedance level, where ω_c is the cutoff frequency of said line and L_{1a} and C_{1a} are, respectively, the inductance and capacitance per unit length of said line at said end, said first-mentioned inductance thereby adjusting the impedance of said line at said end to match exactly over the transmission band the mid-shunt image

impedance of a constant- k filter having a series-reactance arm with a capacitance of

$$\frac{1}{\omega_c} \sqrt{\frac{C_{1a}}{L_{1a}}}$$

5 and a shunt-reactance arm with an inductance of

$$\frac{1}{\omega_c} \sqrt{\frac{L_{1a}}{C_{1a}}}$$

10 5. A wave-signal translating system comprising a transmission line having an impedance which varies exponentially along the length of the line and a terminating circuit for said line comprising a capacitance having a value of

$$15 \frac{1}{\omega_c} \sqrt{\frac{C_{1b}}{L_{1b}}}$$

in series with said line at the end of the line having the higher impedance level, where ω_c is the cutoff frequency of said line and L_{1b} and C_{1b} are, 20 respectively, the inductance and capacitance per unit length of said line at said end, said first-mentioned capacitance thereby adjusting the image impedance of said line at said end to match exactly over the transmission band the mid-series 25 image impedance of a constant- k filter having a series-reactance arm with a capacitance of

$$\frac{1}{\omega_c} \sqrt{\frac{C_{1b}}{L_{1b}}}$$

30 and a shunt-reactance arm with an inductance of

$$\frac{1}{\omega_c} \sqrt{\frac{L_{1b}}{C_{1b}}}$$

35 6. An electrical impedance network comprising a terminal circuit including reactance tending to limit the responsiveness of said terminal circuit over a wide band of frequencies, an auxiliary filter network coupled to said terminal circuit and including said reactance as a full- 40 terminating reactance at one end of said filter, said filter having an m -derived termination at its other end, and a resistive-terminating circuit coupled to said other end of said filter and matching the impedance thereof over the pass 45 band of said filter, whereby the responsiveness of said network is maintained substantially uniform over said pass band.

7. An electrical impedance network comprising a terminal circuit including reactance effectively in shunt across said terminal circuit tending to limit the responsiveness of said terminal circuit over a wide band of frequencies, an auxiliary filter network coupled to said terminal circuit and including said reactance as a full-shunt terminating element at one end of said filter, said filter having an m -derived termination at its other end, and a terminating resistor coupled to said other end of said filter and matching the impedance thereof over the 60 pass band of said filter, whereby the responsiveness of said network is maintained substantially uniform over said pass band.

8. An electrical impedance network comprising a terminal circuit including reactance effectively in series in said terminal circuit tending to limit the responsiveness of said terminal circuit over a wide band of frequencies, an auxiliary filter network coupled to said terminal circuit and including said reactance as a full-series terminating element at one end of said filter, said filter having an m -derived termination at its other end, and a terminating resistor coupled to said other end of said filter and matching the impedance thereof over the pass band of said filter, whereby the responsiveness of said net- 70 75

work is maintained substantially uniform over said pass band.

9. An electrical impedance network comprising a terminal circuit including an inductive element effectively coupled across said terminal circuit and tending to limit the responsiveness of said terminal circuit over a wide band of frequencies, an auxiliary filter network coupled to said terminal circuit and including said inductive element as a full-shunt terminating element 10 at one end of said filter, said filter having an m -derived termination at its other end, and a terminating resistor coupled to said other end of said filter and matching the impedance thereof over the pass band of said filter, whereby the 15 responsiveness of said network is maintained substantially uniform over said pass band.

10. A signal-translating system for operation over a wide range of frequencies comprising a pair of terminals between which there is effectively a substantial reactance tending to limit the response of said system over said range, a filter having a predetermined image impedance over said range and coupled to said pair of terminals, said filter comprising a portion of said reactance 20 as a mid-element of said filter, and an impedance termination coupled to the dead end of said filter proportioned substantially to match the image impedance of said filter over said range, the reactive constants of said dead-end filter being 25 so proportioned relative to said reactance and the operating frequency range that the mean value of the impedance between said pair of terminals over said range is approximately the 30 limiting value that can be maintained therebetween over said range.

11. A signal-translating system for operation over a wide range of frequencies comprising a pair of terminals in series with which there is effectively substantial capacitance tending to 4 limit the response of said system over said range, a filter having a predetermined image impedance over said range coupled to said pair of terminals, said filter comprising a portion of 45 said capacitance as a mid-series element of said filter, and an impedance termination coupled to the dead end of said filter proportioned substantially to match the image impedance of said filter over said range, the reactive constants of said dead-end filter being so proportioned relative to said capacitance and the operating frequency range that the mean value of the admittance between said pair of terminals over said range is approximately the maximum that can be maintained therebetween over said range.

12. A signal-translating system for operation over a wide range of frequencies comprising a pair of terminals across which there is effectively substantial inductance tending to limit the response of said system over said range, a filter having a predetermined image impedance over said range coupled to said pair of terminals, said filter comprising a portion of said inductance as a mid-shunt element of said filter, and an impedance termination coupled to the dead-end of said filter proportioned substantially to match the image impedance of said filter over said range, the reactive constants of said dead-end filter being so proportioned relative to said inductance and the operating frequency range that the mean value of the impedance between said pair of terminals over said range is approximately the maximum that can be maintained therebetween over said range.

HAROLD A. WHEELER.

Certificate of Correction

Patent No. 2,204,712.

June 18, 1940.

HAROLD A. WHEELER

It is hereby certified that errors appear in the printed specification of the above numbered patent requiring correction as follows: Page 2, first column, line 45, for the word "impedance" read *impedances*; page 4, second column, lines 25 and 37, Equations 24 and 26 respectively, for

$$\left(\frac{4y_a}{d}\right)e^{4\pi s/\lambda_0} \text{ read } \left(\frac{4y_a}{d}\right)e^{4\pi s/\lambda_0};$$

lines 42 and 45, Equations 27 and 28 respectively, for

$$\left(\frac{4y_a}{d}\right)e^{4\pi s'/\lambda_0} \text{ read } \left(\frac{4y_a}{d}\right)e^{4\pi s'/\lambda_0};$$

and that the said Letters Patent should be read with these corrections therein that the same may conform to the record of the case in the Patent Office.

Signed and sealed this 3rd day of September, A. D. 1940.

[**SEAL**]

HENRY VAN ARSDALE,
Acting Commissioner of Patents.
